UNITED STATES PATENT OFFICE.

RALPH R. ROOT, OF CLEVELAND, OHIO.

BROODER.

1,138,508.

Specification of Letters Patent.

Patented May 4, 1915.

Application filed May 9, 1908. Serial No. 431,739.

To all whom it may concern:

Be it known that I, RALPH R. Root, a citizen of the United States, residing at Cleveland, in the county of Cuyahoga and State of Ohio, have invented a certain new and useful Improvement in Brooders, of which the following is a full, clear, and exact description, reference being had to the accompanying drawings.

10 My invention relates to brooders and has for its object the provision of a brooder of the type known as the shelf brooder.

This brooder is adapted to be used indoors, being placed upon a shelf, and as is customary, a large number of the individual brooders are housed in the same quarters. The construction of the brooder is such as to allow a free passage of air through the same which greatly improves the sanitary condition of the brooder and the health of the chickens.

Generally speaking, the invention comprises the elements and combinations thereof set forth in the claims.

25 Reference should be had to the accompanying drawings in which—

Figure 1 is a central longitudinal section of the brooder. Fig. 2 is a central longitudinal section of the improved water heater. Fig. 3 is a transverse longitudinal section of the water heater on the line *a—a* of Fig. 2. Fig. 4 is a perspective showing the water heating drum and the radiating tubes. Fig. 5 is a perspective view of the 35 lamp.

The brooder comprises a frame generally represented at 1, which frame supports, in a manner to form the sides thereof, auxiliary frames 2 which are covered with wire netting. These frames are adapted to engage the sides of the main frame 1 and are held in place by any suitable means. The wire netting is held in place by any desired means and allows the free circulation of the air through the brooder.

Within the main compartment is a swinging platform 3 which is adapted to be suspended by four chains 4 that are secured to the frame 1 by means of projecting pins 50 which are secured upon the outside of the frame 1 and engage a link upon each of the chains, thereby supporting the platform 3.

The platform itself is supported upon two transverse members 4', one of the said members being located near each end of the platform. These members are at each of their

respective ends secured to one of the chains 4. It will thus be seen that the platform 3 may be supported in any desired position between the top and bottom of the brooder by placing the desired links of the chains in engagement with the pins. In this manner the distance between the platform 3 and the tubes can be varied to accommodate the chicks as they grow.

Near the forward end of the brooder is a slanting platform 5 which is in proximity to the end of the platform 3, so that the chicks may climb over the end of the platform and down the incline 5 to a running space.

The heating device which is housed in the rear portion of the brooder comprises a water heating drum 6 which has a series of tubes 7 projecting from it, which tubes slant slightly in an upward direction so that a circulation of the heated water may be obtained from the drum through the tubes. These tubes are secured to the heating drum 6 in a suitable manner. The interior of the drum and tubes are in communication with each other, while the outer ends of the tubes are closed. The tubes at their outer ends are held in proper relative position by means of an angle bar 8 to which they are suitably secured. The heating drum and pipes are suitably supported within the brooder by a plate member 9 which extends from wall to wall of the brooder and at a sufficient height above the bottom thereof so that the outer end of the pipes 7 will extend nearly to the top of the frame. The inner wall of the heater 6 engages with the surface of the plate 9 and the end walls of the heater 6 engage with the side walls of the brooder near its rear end. The drums and tubes are held in place by a hook 8' secured in the main frame which hook engages with the angle iron 8. Above the tubes is a frame 10 which is covered with wire netting the same as are the side frames 2. This member is of a size to just fit the top portion of the brooder, and is supported by resting upon the tubes and heater drum. This netting will prevent the chicks from piling one upon another, because they will not be able to get above the tubes.

The heating drum is formed of sheet metal and comprises a top member 11 and depending side members 12 and end members 13. The bottom of the heater is formed by a piece of sheet metal 14 spaced a short

distance from the top which is of less area than the top and is connected to the sides 12 and 13 by means of slanting members 15 and 16. The formation of the heater thus provides a chamber inclosed by the sides 15 and 16 within which a certain volume of heated air is retained so as to supply the heat to the water within the drum.

An auxiliary drum 17 is supported from the drum 6 by means of a vertical pipe 18 and an obliquely slanting pipe 19. The pipe 19 is connected with the heating drum 6 at a point near the lower part of one of the end walls 16. The drum 17 is formed with a central opening 20 into which the burner of the lamp is adapted to project. Any desired means of heating the drum 6 may be employed. However, I have shown an oil lamp to perform that function. The lamp, as shown, is of ordinary construction having an elongated body portion 27, a burner 28 which is adapted to project into the opening 20 in the drum 17, and a flexible spring 29 engaging the bottom. By means of this spring the burner of the lamp is held in contact with the drum 17 at all times when the heating apparatus is in position in the brooder.

Due to the fact that the pipe 19 is in communication with the drum 6 near the lower portion thereof, the cooler water in the drum 6 will pass through the pipe 19 to the drum 17 and thence as it becomes heated, will pass upwardly through the pipe 18 and return again into the drum 6. This will secure a circulation of the coldest water through the drum 16 which will at all times keep the burner cool and prevent the over-heating of the burner.

A sight tube 21 is provided, which projects through the top and bottom of the drum 6 in a slanting direction, and is so placed that the eye of an observer may see the flame of the lamp by looking through the same and thus obviating the necessity of the removal of the lamp when it is desired to inspect the condition of the flame. The outer end of this tube is closed by a cap 22 which may be formed of any suitable material preferably of a transparent material which will not be affected by the heat, such as mica.

A second tube 23 projects through the top and bottom of the drum 6 near one end thereof, and extends below the bottom 14 a distance midway between the bottom 14 and the lower extremity of the sides 12. This construction provides that a body of heated air will always be in contact with the bottom 14 of the drum. Above the top of the drum 11 this pipe is formed with an elbow and a straight pipe 24 is sleeved upon the upper portion of the elbow. The pipe 24 is provided with a shield extending across its outer end. The pipe 23 will conduct away

the products of combustion, and by virtue of the shield 25 at the outer end of the pipe, the air currents, which would tend to enter the pipe 24 and carry the fumes to the space occupied by the chickens, are prevented from entering.

A cover 26 is provided, which forms a closure for the lower part of the heating drum. The cover has an opening through which the drum 17 projects. This cover prevents any of the gases or products of combustion contained within the space inclosed by the lower walls of the drum 6 from escaping into the part of the brooder occupied by the chickens.

The drum 6 is provided with a capped opening 26^a which allows the filling of the tank with water.

The operation of the device which I have described is as follows: Tank 6 is provided with a suitable amount of water and the burner is placed in position beneath the same so that the burner of the lamp will engage with the walls of the passage 20 in the drum 17. As the water becomes heated, it will tend to circulate through the tubes 7 and so supply heat to the chicks which are contained within the brooder. Upon the return of the water from the pipes 7 to the drum 6, the cooler water will sink toward the lower portion of the drum 6 and will circulate through the pipes 7.

It will be obvious that the device which I have above described secures several important and useful results. The drum which surrounds the burner keeps the burner cool and so prevents the over-heating of the burner and likewise prevents the brooder from catching on fire. Again, practically all the heat supplied by the burner is saved, for the heat absorbed due to the cooling of the burner is given to the water in the main drum, and thus practically all the heat developed is utilized; but what is the most practical of the advantages, the quantity of oil consumed by the lamp under these conditions is materially reduced, for the reason that substantially all the heat is saved and utilized. Consequently, the lamp does not have to be forced to supply heat and so the quantity of oil consumed will be less.

The provision of the removable sides is of great advantage in that the tray 3 can be removed and cleaned very quickly and easily and by virtue of the fact that the sides are composed of wire netting, the air may circulate freely through the brooder which will keep the chicks in a healthy condition.

I claim:

1. The combination with a heating drum, a heat radiating member extending therefrom, an auxiliary drum beneath said heating drum and provided with a central opening, a burner for heating the first drum, which burner projects into the opening in 120

the auxiliary drum, and pipes connecting the two drums, the second drum being connected only with the first drum.

2. The combination of a heating drum, a plurality of pipes communicating at one of their ends with said drum and closed at their opposite ends, a cooling drum, pipes connecting and suspending said cooling drum from the first drum, the cooling drum being provided with an opening, a burner for heating the first drum, said burner extending into the opening in the second drum.

3. The combination of a heating drum, a burner for heating the said drum, a second drum having a central opening into which the burner extends, a substantially vertical pipe connecting the drums, and a second pipe connecting the second drum with the first drum at a point thereon lower than that at which the first pipe connects, thereby causing a circulation of fluid in the said drums.

4. The combination of a fluid heating drum, a plurality of non-communicating heat radiating members connected only to the drum, a second drum provided with a central opening, a burner for heating the first drum and extending into the opening in the second drum, and pipes connecting the second drum to the first drum only.

5. The combination of a fluid heating drum, a plurality of pipes which are connected with the said drum at one of their ends and closed at the opposite ends, a second drum depending from the first drum and having a central opening, a burner for heating the first drum and extending into the opening in the second drum, and pipes connecting the said drum with the first drum only.

6. The combination of a heating drum having a top and bottom member, the bottom member being of less area than the top

member, said heating drum also having a hollow portion depending from said drum, a second drum below the first drum, a pipe connecting the second drum with the main part of the first drum, and a pipe connecting the second drum with a part of the hollow portion, the point of connection of the second pipe with the first drum being below the point of connection of the first pipe with the first drum.

7. In a brooder, a heating drum comprising a top and bottom member, the bottom being of less area than the top member, flanges depending from the top member of the drum, slanting flanges depending from the bottom member of the drum and being secured to the lower edges of the first mentioned flanges, a second drum below the first drum, a pipe connecting the second drum with the first mentioned drum, and a second pipe connecting the second drum with the first mentioned drum at a part thereof bounded by the flanges.

8. In a brooder, a heating drum, a second drum provided with a central opening below the first drum, pipes connecting the two drums, a burner for heating the first drum and extending into the opening in the second drum, the first drum being provided with a recessed portion in the underside thereof adapted to retain a portion of the products of combustion, a flue pipe communicating with the recessed portion, and a cover closing the recessed portion and having an opening with which the second drum co-operates.

In testimony whereof, I hereunto affix my signature in the presence of two witnesses.

RALPH R. ROOT.
